United States Patent Office

Des. 203,863

Patented Feb. 22, 1966

203,863

DESK LAMP

Manfred Neumann, River Edge, N.J., assignor to Lightolier Incorporated, a corporation of New York

Filed Jan. 25, 1965, Ser. No. 83,548

Term of patent 14 years

(Cl. D48—20)

FIG. 1 is a perspective view of the desk lamp showing my new design taken from the top thereof,

FIG. 2 is an end elevational view thereof,

FIG. 3 is a top plan view thereof, and

FIG. 4 is a bottom plan view thereof.

I claim:

The ornamental design for a desk lamp, substantially as shown.
